UNITED STATES PATENT OFFICE.

PETER H. BETHEA, OF WASHINGTON, DISTRICT OF COLUMBIA.

WHIP-SOCKET LOCK.

1,241,331.

Specification of Letters Patent. Patented Sept. 25, 1917.

Application filed March 30, 1917. Serial No. 158,704.

To all whom it may concern:

Be it known that I, PETER H. BETHEA, a citizen of the United States and State of South Carolina, residing at 2023 E street 5 northwest, in the city of Washington and District of Columbia, have invented new and useful Improvements in Whip-Socket Locks, of which the following is a specification.

10 This invention relates to carriages and wagons, and more especially to whip socket locks; and the object of the same is to produce a new and improved form of lock of this character adapted to hold the butt end 15 of the whip in the socket so that it may not be removed by an unauthorized person.

The invention contemplates improvements in the details of structure, which will be hereinafter more fully described and 20 claimed, and which are illustrated in the accompanying drawings wherein:—

Figure 1 is a perspective view of this improved whip socket entire, showing it attached to one corner of the dashboard.

25 Fig. 2 is a vertical section through the several parts of the device connected.

Figs. 3—4—5 and 6 are details of the parts yet to be described.

Referring now to the drawings, the numeral 1 designates a tubular barrel which is 30 closed at its lower end as shown at 2 and is provided at its upper end with a series of parallel spring tongues 3, each of which has an inturned and serrated jaw 4 at its upper 35 extremity. Surrounding said tongues and spaced slightly therefrom is a sleeve 5, whose lower end is riveted as at 6 to the upper end of the barrel, and screwed at 7 to the upper end of the sleeve is an ornamental hollow knob or ball 8 which is intended to finish off the upper end of the structure and give it a neat appearance. The spring tongues 3 work freely inside the 40 sleeve 5, and their jaws are intended to grip the butt of the whip W at a point somewhere within the ornamental knob 8 as seen in Fig. 2. For causing said gripping action, a slidable collar or annular wedge, best seen in Fig. 5, is provided, the same having 45 its body 10 rather thicker at the upper edge than at the lower edge so that as it is forced downward it deflects the tongues 3 inward. For moving it downward it is provided with 50 a strip member 11 which hangs to a point below the sleeve 5 and is visible in Fig. 1, and the lower end of this member may be

bent outward so as to provide a suitable hand-hold. A coiled spring 12 surrounds the tongues 3, its lower end resting on a shoulder 13 where said tongues unite with 60 the barrel 1, and its upper end pressing against the lower end of the wedge-body 10. Said body is provided internally with a series of upright ribs 15 which move between certain of the tongues and permit the wedge 65 to have a reciprocating movement but prevent it from rotating, and therefore the strip 11 always hangs at one point which is toward the user. When now the strip is drawn upon it is obvious that the wedge will 70 be moved downward between the sleeve 5 and the tongues 3, and the jaws 4 at the upper ends of the latter will be thrown inward against the butt of the whip; and when the strip 11 is released, the spring 14 75 will move the wedge upward again and free the whip.

The locking feature of this device is as follows:—In the outer face of the wedge is provided an upright series of recesses 20. 80 Directly opposite this series of recesses stands the spring member best seen in Fig. 6. It is composed of an outer leaf 21 which may be riveted or otherwise secured within the sleeve 5, and an inner leaf 22 depending 85 from the upper end of the outer leaf and normally springing inward therefrom; and the lower end of the inner leaf carries a tongue 23 adapted to enter any of the recesses 20. Secured within the sleeve is a 90 lock whose case is best shown at 24, with its key-hole 25 opening through the forward side of the sleeve where the user may insert a key. The bolt 26 of this lock is here shown as shot, and when this bolt is projected it is 95 passed behind the lower and free end of the inner leaf 22, between it and the outer leaf 21, and prevents said free end and therefore the tongue 23 from moving so as to disengage the recesses 20. Therefore when the 100 wedge is drawn down by the strip 11 to such a degree as is permitted by the inward movements of the tongues and jaws, one of the recesses will engage the tongue 23. Thereafter 105 the operator by shooting the bolt of the lock projects it behind the lower end of the inner leaf, and prevents the disengagement of the tongue from the recess and therefore the upward movement of the wedge. The lock may be of such type as requires a key, and if so he carries the key with him when he leaves the vehicle. On his return he inserts 110

the key and retracts the bolt, when the leaf 22 is free to move. In order to move it from the exterior of the device, I provide a handle 27 which is connected with the inner leaf 22 5 and passes farther through a hole 28 in the outer leaf and in the front wall of the sleeve, and is headed at its free end so that the operator may grasp it. Having retracted the bolt, he now grasps the handle 10 and draws upon it, with the result that the tongue is retracted and disengaged from the notch, 20, in which it formerly rested, and the spring 14 causes the wedge immediately to rise so that the jaws 4 release the butt of 15 the whip. The parts are all preferably of metal, suitably treated to prevent rust and possess a neat appearance; and I do not wish to be limited to details further than as hereinafter set forth.

20 20. What is claimed as new is:—

1. In a whip socket lock, the combination with a barrel having a series of spring tongues at its upper end, each provided with an inwardly facing jaw, and a sleeve secured to the barrel and surrounding said tongues; of an annular wedge interposed between the sleeve and tongues, a spring for holding the wedge normally raised, a strip 25 depending from the wedge between the barrel and sleeve and having a hand-hold outside the barrel for moving the wedge downward against the tension of said spring, a latch on the sleeve for engaging said wedge in its depressed position, and a lock for the latch.
2. In a whip socket lock, the combination with a tubular barrel shouldered at its upper end and continued thence upward in spring tongues, a sleeve secured at its lower end to

the upper end of said barrel and surrounding said tongues, a coiled spring surrounding the tongues and resting on said shoulder, and an annular wedge whose lower end rests on said spring and whose outer face is provided with an upright series of recesses; of means for manually depressing the wedge from the exterior of the sleeve, a spring latch on its interior having a tongue adapted to engage any of said recesses, means for locking the latch to prevent the disengagement of the tongue from a recess, and means for retracting the latch when the lock is retracted. 40

3. In a whip socket lock, the combination with a tubular barrel shouldered at its upper end and continued thence upward in spring tongues, a sleeve secured at its lower end to the upper end of said barrel and surrounding said tongues, a coiled spring surrounding the tongues and resting on said shoulder, 45 and an annular wedge whose lower edge rests on said spring and whose outer face is provided with an upright series of recesses; of means for manually depressing the wedge from the exterior of the sleeve, a latch of 50 inverted V-shape whose outer leaf is secured within the sleeve and whose inner leaf has a tongue adapted to engage any of said recesses, a handle connected with said inner leaf and extending through the outer leaf 55 and sleeve to within reach of the user, and a lock secured within said sleeve and having a bolt adapted to be raised behind the inner leaf to prevent the movement of the latter to disengage it from said recesses. 60

75

In testimony whereof I affix my signature.

PETER H. BETHEA.
